(57) **CLAIM**

The ornamental design for a handbag cover, as shown and described.

DESCRIPTION

FIG. 1 is a perspective view of one embodiment of a handbag cover showing the new design with an optional pocket.

FIG. 2 is a perspective view of the handbag cover of FIG. 1 with an optional flap raised to show an optional window.

FIG. 3 is a front view of the handbag cover of FIG. 1.

FIG. 4 is a rear view of the handbag cover of FIG. 1.

FIG. 5 is a right view of the handbag cover of FIG. 1.

FIG. 6 is a left view of the handbag cover of FIG. 1.

FIG. 7 is a top view of the handbag cover of FIG. 1; and,

FIG. 8 is a bottom view of the handbag cover of FIG. 1.

The broken lines showing the flaps and window are for the purposes of illustrating environment and form no part of the claimed design.
